UNITED STATES PATENT OFFICE.

JACOB DEBING, OF McVILLE, NORTH DAKOTA.

FOLDING EXTENSION-LADDER.

1,179,810.

Specification of Letters Patent.

Patented Apr. 18, 1916.

Application filed September 25, 1915. Serial No. 52,644.

To all whom it may concern:

Be it known that I, JACOB DEBING, a citizen of the United States, residing at McVille, in the county of Nelson and State 5 of North Dakota, have invented new and useful Improvements in Folding Extension-Ladders, of which the following is a specification.

This invention relates to foldable extension ladders and it consists in the novel features hereinafter described and claimed.

An object of the invention is to provide a ladder structure consisting of sections detachably connected together, the said sections 15 being collapsible or foldable whereby they may occupy but little space while in storage, transportation or otherwise when not in use as a ladder. With this object in view the sections are composed of side bars pivotally connected together in the manner of lazy tong levers, there being provided upon the extension section of the ladder pivotally mounted clips adapted to engage over the 20 upper ends of the uppermost side bars of the body section of the ladder. Both sections of the ladder are provided with hooks which are engageable with the upper ends 25 of the same pairs of side bars whereby the side bars are held at extended positions with relation to each other. Some of the side 30 bars of the sections are provided with rounds upon which a person may step when ascending or descending the ladder.

In the accompanying drawings:—Figure 35 1 is a side elevation of the ladder showing the sections connected together. Fig. 2 is an edge elevation of the same. Fig. 3 is a side elevation of one of the ladder sections showing the parts thereof collapsed.

40 The ladder comprises a body section 1 which is composed of a series of side bars pivotally connected together at points midway between their ends, the said side bars being indicated at 2. Some of the side bars 45 2 are connected together by rounds 3 and the upper ends of the uppermost bars 2 are chamfered or beveled as at 4. The side bars 2 are connected together in the manner usually employed for connecting lazy tong levers, consequently when the said side bars 50 are folded with relation to each other, the body portion 1 of the ladder is in a collapsed condition.

Hooks 5 are provided at the upper ends 55 of two of the lowermost side bars 2 and are

adapted to engage the pivot 6 which connects two of the lowermost side bars 2 with two of the next adjacent side bars 2 of the body structure 1.

The ladder extension 7 is composed of side 60 bars 8 pivotally connected together in a manner similar to the connection between the side bars 2 of the body section of the ladder and some of the side bars 8 carry rounds 9. Hooks 10 are mounted at the 65 upper ends of two of the lowermost side bars and are engageable with pivots 11 which connect the upper ends of the other two lowermost side bars 8 with the lower 70 ends of two of the side bars at the upper 75 portion of the ladder extension 7. The lowermost side bars 8 of the ladder extension 7 are provided with pivotally mounted clips 12 which are adapted to engage over the chamfered ends 4 of the uppermost side 80 bars of the body section 1 of the ladder when the extension section is applied thereto. When the extension section is applied to the body section, the edges of the lowermost side bars 8 of the extension section 85 lie against the edges of the uppermost side bars 2 of the body section 1 and the said sections are held in close proximity to each other by means of the clips 12 hereinbefore described.

From the foregoing description taken in conjunction with the accompanying drawing it will be seen that when a long ladder is desired, the extension section is applied to the body section 1 and secured thereto 90 in the manner indicated and when the sections are thus connected, a person may ascend or descend the ladder by stepping upon the rounds 3 and 9 of the two sections. If a short ladder is desired one or the other 95 of the said sections may be used. When it is desired to collapse and fold the sections, the uppermost or extension section is disconnected from the body section 1 and the hooks 5 and 10 are disconnected from the 100 pivots 6 and 11 and consequently both of the said sections may be collapsed or folded and will occupy but small space.

It will be seen that a ladder structure of simple design is provided and when the 105 parts are connected together and extended, the ladder is substantial and owing to the structural arrangement of the parts, the ladder is light and may be readily moved from point to point.

Having described the invention what is claimed is:

A ladder comprising a plurality of sections each composed of side bars pivotally connected in the form of lazy tongs, rounds carried by some of the side bars of both sections, hooks pivotally connected with the ends of some of the side bars of both sections and adapted to engage pivots at the ends 10 of other side bars of the same section whereby the sections are held in extended position, the uppermost ends of the uppermost side bars of one section being beveled, the side edges of the lowermost side bars of the

other section adapted to fit against the edges 15 of the uppermost side bars of the first mentioned section, and clips pivotally mounted upon the lowermost side bars of the second mentioned section and adapted to engage over the beveled ends of the uppermost side 20 bars of the first mentioned section.

In testimony whereof I affix my signature in presence of two witnesses.

JACOB DEBING.
